Primary Examiner — Melanie Pellegrini*(74) Attorney, Agent, or Firm* — Bochner PLLC; Andrew D. Bochner(57) **CLAIM**

The ornamental design for a ring, as shown and described.

DESCRIPTION

FIG. 1 is a top, front, right-side, perspective view of a ring; FIG. 2 is a front elevation view thereof; FIG. 3 is a rear elevation view thereof; FIG. 4 is a left-side elevation view thereof; FIG. 5 is a right-side elevation view thereof; FIG. 6 is a top plan view thereof; and, FIG. 7 is a bottom plan view thereof.

The broken lines shown in the drawings represent portions of the ring which form no part of the claimed design.
